UNITED STATES PATENT OFFICE.

GEORGE W. BATTLE, OF SAVANNAH, GEORGIA.

RERAILER.

Application filed February 14, 1925. Serial No. 9,302.

To all whom it may concern:

Be it known that I, GEORGE W. BATTLE, a citizen of the United States, residing at Savannah, in the county of Chatham and 5 State of Georgia, have invented certain new and useful Improvements in Rerailers, of which the following is a specification.

This invention relates to a railroad car re-railor and consists of certain improvements 10 set forth in this specification.

An object of the invention is to provide a re-railor or car replacement frog adapted to re-rail cars that are off the track either to the right or left thereof and coming or going 15 in either forward or reverse direction.

Another object of the invention is to provide a re-railor that will fit rails of various sizes or weights and remain stationary during the re-placement of a car on the rails.

20 Another object of the invention is to provide re-railers for each rail of the track practically identical in construction except reversed from left to right or vice versa.

With these and other objects in view 25 which will be apparent as the description proceeds, I will now describe my invention in connection with the accompanying drawings in which:

Figure 1 is a plan view of my re-railers arranged to replace cars from the right hand side of the track.

Fig. 2 is a plan view of my re-railers arranged to replace cars from the left hand side of the track.

35 Fig. 3 is a view from beneath of one re-railor.

Fig. 4 is a similar view of the other re-railor.

Fig. 5 is a section on the line 5—5 of Fig. 10 6, and,

Fig. 6 is a plan view of a slight modification of my device.

1—1 and 2—2 represent ordinary railroad rails of a track and 3 the ties.

45 I preferably provide bolt holes 6 in my re-railers and on their upper surfaces a channel portion 7—7', leading to a throat 8—8'. The channel portions are bounded by inner ledges 9—9' and outer ledges 10, 10'.

50 Hook-like projections 11, 11' project inwardly from both the right hand and left hand re-railers. It will be noticed that these hook-shaped projections 11, 11' extend outwardly and thence downwardly to hook over the rails 1—1 or 2—2 when cars are 55 to be run over the re-railers back onto the

rails. It will also be noticed in Fig. 1 that the hook on the right hand re-railor is resting on the rail 2—2. The hook (not shown) in Fig. 1 does not rest on the rail 1—1, but 60 to one side thereof. In Fig. 2 the hook 11' on the left hand frog rests over the rail 1—1 while the hook 11 on the right hand frog is to one side of the rail 2—2 and to correspond with the inclination of the car after 65 it has left the rails the left hand frog would ordinarily be placed in advance of the right hand frog of Fig. 1, although this is not invariably the case and the frogs will be arranged in the positions to suit the particular circumstances of each case. 70

The under side of the frogs are best illustrated in Figs. 3 and 4 and comprise channel portions 15—15' bounded on either side by ledges 16—16' and 17—17'. The 75 channel portions 15—15' are wider at their lower portions in Figs. 3 and 4 and gradually narrowed to a throat portion opposite the hooks 11—11'. These channel portions are adapted to fit over the rails 1—1 or 80 2—2, the wide lower portions of 15—15', allowing the frogs to be inclined more or less to the rails, the throat portion fitting more or less snugly the rail therein.

It will be observed that both frogs are 85 provided with the hook portion 11—11' and with the channel portion 15—15' either of which is adapted to fit over the rail as shown in Figs. 1 and 2, hence my two frogs are adapted to re-rail a car from the right hand side of Fig. 1 going to the left in Fig. 1, or to re-rail a car from the left as shown in Fig. 2 movable in the same direction. It is also apparent that the frog may re-rail a car moving in the opposite direction from either 90 the left or the right of the track.

I may provide lugs 20 on the lower portions of the frogs to prevent their slipping during the re-railing operation.

Fig. 6 shows a slight modification of my 100 device having a lug 21 thereon to rest against the side of the rail to assist in steadying the same when in use.

The operation of my re-railor is apparent to those skilled in this art from the foregoing description. To re-rail a car the frogs are arranged as shown in Figs. 1 or 2. One of the frogs in each position having its hook 11 or 11' over the rail and the other frog lying on top of the rail, the rail resting 105 in the channel portion 15 or 15', this channel being wider at its outer portion permits 110

the frog to be inclined to the rail to adapt it to receiving the de-railed car in a variety of positions.

What I claim as new is:

- 5 1. A re-railer frog having on its upper surface ledges inclined to each other and an intermediate channel portion, and on its lower surface ledges inclined to each other and an intermediate channel portion, a hook 10 on the side of the re-railer at the end of the channel portion on the lower surface of the re-railer, said hook being adapted to fit over the rails and said lower channel portion being also adapted to receive the rail but allowing horizontal adjustment of the frog on the rail.
2. A re-railer for cars and the like comprising a frog having on its upper surface ledges inclined to each other and an intermediate channel portion to guide the car to 20 the rail, a hook on the side of the frog adapted to embrace the rail, said frog also

having on its under surface ledges inclined to each other and a channel portion between the ledges with its throat portion opposite 25 said hook, a projection having a bolt hole therein adapted to receive a bolt and projections on the lower surface of the frog to prevent its slipping.

3. A pair of frogs for re-railing a car 30 on either side of the track and movable in either of two directions, each frog having an inwardly projecting hook to fit over a rail and each frog having ledges on their upper and lower surfaces, the ledges being 35 inclined to each other and the lower channel sections of each frog being adapted to fit over a rail and horizontally tiltable to adjust it to different positions of the car being re-railed.

In testimony whereof I hereunto affix my signature.

GEORGE W. BATTLE.
